Attorney

UNITED STATES PATENT OFFICE.

CLEMENT V. WILLIAMS, OF LOVELAND, OKLAHOMA.

MARKING DEVICE FOR HENS' NESTS.

1,240,277.

Specification of Letters Patent. Patented Sept. 18, 1917.

Application filed May 9, 1917. Serial No. 167,441.

To all whom it may concern:

Be it known that I, CLEMENT V. WILLIAMS, a citizen of the United States, and resident of Loveland, in the county of Tillman and State of Oklahoma, have invented 5 certain new and useful Improvements in Marking Devices for Hens' Nests, of which the following is a specification.

This invention relates to new and useful 10 improvements in marking devices, and more particularly to marking devices adapted to be applied to hens' nests, and the primary object of the invention relates to the formation of a marking device of this character which 15 will designate the various hens which are laying, by marking the same upon a use of the nest, and which will also mark any other animals that would enter the nest for the purpose of robbing the same.

20 Another object of the invention is to provide a marking device of this character which comprises a device adapted to sift a quantity of marking powder upon the hen upon entering the nest, and said device is 25 adapted to contain a powerful and effective germicide in addition to the marking powder, so as to enable the device to be used as a disinfectant in addition to being a marker.

Another object of the invention is to provide 30 a device of this character which is easily and simply constructed, inexpensive to manufacture, and one which will be very efficient in operation.

With these and numerous other objects in 35 view my invention consists of the novel features of construction, combination and arrangement of parts which will be herein referred to and more particularly pointed out in the specification and claim.

40 In the accompanying drawing:

Figure 1 is a perspective view showing the marker applied to the conventional type of hen's nest, and

45 Fig. 2 is a vertical section through the marker.

In describing my invention I shall refer to the drawing in which similar reference characters designate corresponding parts throughout the several views. The numeral 50 1 designates a hen's nest of the conventional type, the same being provided with an outlet opening 2 in one wall thereof, and the marker which is designated in its entirety by the numeral 3, is positioned through the 55 top of the nest, adjacent said outlet opening. Although the marker is shown applied to a

single nest, it is obvious that a number of these markers may be applied to a plurality of nests, where a panel is provided, the same having a number of outlet openings therein. 60 A marker is provided for each opening, so that the marking material will be sprinkled on the hen upon entering the nest.

The marker comprises a reservoir 4, which is in the shape of a funnel-shaped hopper, and which is adapted to contain a quantity of marking powder, the same being preferably the ordinary type of Venetian red or white powder, which will serve to distinguish any colored strain of hen, and 70 which will also mark cats or dogs, etc., when sprinkled thereon. The lower end of the reservoir 4 is connected with a tubular member 5, which is positioned through the top of the nest 1, said tubular member being 75 vertically adjustable therein, so as to position the device according to the various sized openings which it is associated with. Secured to the lower end of the tubular member 5 is a flexible brush head 6, which comprises a coiled spring 7, having its upper end secured around the lower end of the tubular member, and projecting downwardly a portion of the brush which is designated by the numeral 8 being secured within the lower 80 end of the spring, while the other portion 85 9 of said brush surrounds the spring and is secured thereto by an annular band 10. This affords a simple means for securing the brush head in connection with the reservoir, 90 and permits the marking material to flow into engagement with the interior of the brush, so that upon movement of the brush the powder is allowed to drop therefrom 95 upon the hen or animal that creates said movement.

To prevent the marking powder from congesting as it flows through the tubular member 5, I have provided a member 11, that extends through said member, and projects 100 also through the reservoir, and into the brush head. This member 11 is preferably a flat steel spring, that is formed very thin, and which when in position will prevent any congestion of the powder during its 105 passage through the tubular member to the brush. When desired a quantity of any efficient germicide may be added to the marking powder, so that the device may be used as a disinfectant.

110 In operation when the marker is positioned, as clearly shown in Fig. 1 of the

drawing, upon the hen entering the nest through the opening 2, the brush head 6 will be engaged, and a quantity of marking powder will be sprinkled on the hen. This 5 will positively mark the hen, and enable the poultryman to determine which hens are laying, and which are not laying. This marker will also correspondingly mark animals such as cats and dogs, or wild 10 animals, that enter the nest for the purpose of robbing the same. This type of marker requires very little attention, as it is only necessary to keep the reservoir filled with marking powder, said reservoir being easily 15 accessible as it is positioned outside of the nest.

From the foregoing description, taken in connection with the accompanying drawing, the advantages of the construction and of 20 the method of operation will be readily apparent to those skilled in the art to which the invention appertains, and while I have

described the principle of operation of the invention, together with the device which I now consider to be the best embodiment 25 thereof, I desire to have it understood that the device shown is merely illustrative, and that such changes may be made when desired as are within the scope of the claim appended hereto.

Having fully described my invention, what I claim as new, and desire to secure by Letters Patent, is:

A marking device of the class described comprising a reservoir, a tubular member connected therewith, a coiled spring surrounding the free end of said tubular member, a brush head carried by said coiled spring, and a flat steel spring extending through the tubular member and projecting 40 into the reservoir and brush head.

In testimony whereof, I affix my signature hereto.

CLEMENT V. WILLIAMS.
